(57) **CLAIM**

The ornamental design for a solar powered insect exterminator, as shown and described.

DESCRIPTION

FIG. 1 is a perspective view of the solar powered insect exterminator;

FIG. 2 is a front elevational view, the rear elevational view, the left and right side elevational views being the same;

FIG. 3 is a top plan view; and,

FIG. 4 is a bottom plan view.

The broken line showing of environment in the drawings is included for the purpose of illustrating only and forms no part of the claimed design.
